US00D706815S

(12) **United States Design Patent**
Danhope et al.

(10) **Patent No.:** **US D706,815 S**
(45) **Date of Patent:** **** Jun. 10, 2014**

(54) **DISPLAY SCREEN WITH GRAPHICAL USER INTERFACE**

(75) Inventors: **Stefanie Danhope**, Seattle, WA (US);
March Rogers, Bellevue, WA (US)

(73) Assignee: **Microsoft Corporation**, Redmond, WA
(US)

(**) Term: **14 Years**

(21) Appl. No.: **29/423,195**

(22) Filed: **May 30, 2012**

(51) LOC (10) Cl. **14-04**

(52) U.S. Cl.

USPC **D14/489**; D14/491

(58) **Field of Classification Search**

USPC D14/489, 491; 715/715

See application file for complete search history.

Primary Examiner — Karen E Kearney

(74) Attorney, Agent, or Firm — Banner & Witcoff, Ltd.

(57) **CLAIM**

The ornamental design for a display screen with graphical user interface, as shown and described.

DESCRIPTION

The FIGURE is a front view of a display screen with graphical user interface showing our new design.

The broken line showing of the remainder of the user interface and display screen is for environmental purposes only and forms no part of the claimed design.

1 Claim, 1 Drawing Sheet
